UNITED STATES PATENT OFFICE.

LOUIS KELLNER, OF BROOKLYN, NEW YORK.

ELECTRIC SWITCH.

1,377,778.

Specification of Letters Patent.

Patented May 10, 1921.

Application filed December 3, 1917. Serial No. 205,141.

To all whom it may concern:

Be it known that I, LOUIS KELLNER, a citizen of the United States, and resident of the borough of Brooklyn, county of 5 Kings, city and State of New York, have invented certain new and useful Improvements in Electric Switches, of which the following is a specification.

This invention relates to manually operable electric switches and has for one of its objects the provision of a switch in which the circuit is adapted to be closed and broken by mechanism operating with a rapid snap action and actuated by a swinging 15 switch lever or handle.

A further object is to provide eccentric means for reciprocating the movable contact means into and out of circuit-closing position, and another important object of the 20 invention is to provide simple means for causing said eccentric means to operate the movable contact means with a snap action as the switch handle reaches the limit of its throw in either direction.

Another object of the invention is to 25 provide rotary cam means actuated by a swinging switch lever for releasing power-operated means as the switch lever reaches the limit of its throw in either direction to permit said power-operated means to actuate 30 the circuit-making and breaking means with a snap action.

A further important object of the invention is to provide simple means operable to 35 reciprocate the movable contact means, either toward or from circuit-closing position, with a quick snap action, said means being controlled by the movement of a swinging switch lever or handle.

Another object of the invention is to 40 provide means for preventing access to the fuse plugs except when the switch is in "off" position;

In the drawings, Figure 1 is a vertical 45 longitudinal sectional view of the switch, taken on the line I—I of Fig. 2, the switch being shown in "off" position;

Fig. 2 a sectional plan on the line II—II of Fig. 1;

Fig. 3 a vertical longitudinal section on the line III—III of Fig. 2, the switch being shown in position to close the circuit;

Fig. 4 a vertical central transverse section, the switch being shown in "off" position;

Fig. 5 a fragmentary horizontal section taken through the fuse box;

Figs. 6, 7 and 8 detail sectional views showing the positions assumed by the operating mechanism when the switch lever is in 60 "off" position, an intermediate position, and "on" position, respectively;

Figs. 9 and 10 detail side elevations showing opposite sides of the eccentric means for shifting the movable contacts;

Fig. 11 a detail side elevation of the releasing cam disk;

Fig. 12 a horizontal section on the line XII—XII of Fig. 11;

Fig. 13 a detail view showing the switch 70 lever or handle; and

Fig. 14 a vertical transverse section on the line XIV—XIV of Fig. 10.

Referring to the various parts by numerals, the switch is provided with a base 1 of 75 porcelain or other suitable material, upon which the parts are mounted, and the entire switch mechanism is inclosed in an outer box-like casing held to one face of the base in any suitable manner. The casing is 80 formed with side walls 2, end walls 3, and a cover 4 hinged to one of the end walls at 5. The casing is divided into an outer compartment and an inner compartment by a partition or division plate 6 having a rectangular 85 opening 7 substantially centrally thereof. A substantially U-shaped frame comprising side members or plates 8 and 9 and a base plate 10, is held to the base 1 by suitable screws 11, or other fastening means, and 90 the side members 8 and 9 of said frame extend through the opening 7 in the partition 6 and into the outer compartment to a point below the cover 4 of the casing.

A rod 12 is supported at its ends in plates 95 8 and 9 adjacent the upper ends of said plates, and a sleeve 13 is rotatably mounted on said rod and is formed with reduced angular end portions 14 and 15. A switch lever or handle 16 is held to the angular end 100 portion 14 of said sleeve and is adapted to rotate said sleeve through slightly more than half a revolution in either direction, said handle being formed with an angular opening 17 through which the angular end 105 portion of sleeve 13 extends. A releasing cam or disk 18 is held to the angular end portion 15 of sleeve 13 to rotate therewith, said disk being formed with an angular opening 19 through which the end 15 of the 110

sleeve extends, and being also formed with a groove 20 in one face thereof extending through an arc of slightly more than 180° and formed with inclined or cam portions 21 and 22 at opposite ends thereof.

An eccentric 23 is loosely mounted on the rod 12 and is formed with a groove 24 in one face thereof, concentric with rod 12 and extending through an arc of 180°. Openings 10 25 and 26 extend through the eccentric 23 at opposite ends of groove 24, said openings being formed with enlarged portions 27 and 28, respectively, in the face of the eccentric opposite the face formed with groove 24. 15 A short headed pin 29 fits loosely in opening 26 and a similar pin 30 fits loosely in the opening 25, the heads of said pins being adapted to pass into and out of the enlarged portions 27 and 28 of said openings and 20 groove 20 in releasing disk 18, as shown more clearly in Fig. 4, and the shanks of said pins being of such length that the ends thereof are flush with the bottom of groove 24 in eccentric 23 when the heads are forced 25 into portions 27 and 28 by the inclined cam ends of groove 20. The heads of the pins are preferably rounded, as shown, and correspond in thickness with the depth of the enlarged portions 27 and 28 of openings 25 and 30.

An eccentric strap 31 extends about the eccentric 23 and is formed with a stem 32 connecting at its lower end by a pin 33 with one arm of a bracket or angle plate 34 held to the outer face of a block 35 of suitable insulating material. The block 35 is guided on the frame members 8 and 9 which extend through openings 36 and 37 in said block, and the block is adapted to be reciprocated by the eccentric from the position shown in Figs. 1 and 4 to the position shown 35 in Fig. 3 when the switch lever is operated, as more fully hereinafter described. Two pairs of movable contacts or brushes 38 and 39 are held to the inner face of the block 35 and are electrically connected with two pairs of fuse-plug-holding clips 40 and 41 on the outer face of block 35 by screws or bolts 42 and 43. A pair of fuse plugs 44 are held at 50 their ends in the pairs of clips 40 and 41, and said plugs and clips are inclosed by a fuse-box or inclosing cover comprising two sections 45 and 46 hinged to rods 47 and 48 supported in the opposite ends of bars 49 held to opposite sides of block 35 by screws 50 and preferably countersunk in said block, as shown. The sections 45 and 46 of the fuse box or cover are preferably provided with interlocking portions or latch means 51, as 55 shown. The pairs of contact brushes 38 and 39 are adapted to engage pairs of stationary terminals or contacts 52 and 53, held to the base 1, when the block 35 is moved toward the base. A motor spring 54 is coiled about 60 the sleeve 13 and the ends 55 and 56 thereof

project at one side of said sleeve in different planes. The switch handle 16 is provided with an inwardly projecting portion or pin 57 and the eccentric 23 is provided with an oppositely projecting portion or pin 58, both of said pins extending between the projecting end portions 55 and 56 of the spring 54. 70

With the parts in "off" position, as shown in Figs. 1, 2, 4 and 6, when it is desired to close the circuit the switch handle or lever 16 is swung upwardly and toward the left, and then downwardly to the position shown in Fig. 3, through an arc of slightly more than 180°. As the switch lever 16 is swung about its pivot the pin 57 on said lever forces the 75 end 57 of spring 54 before it, thus winding said spring or placing the same under tension, as the eccentric 23 and pin 28 carried thereby are held against rotation by a pin 59 extending through an aperture in frame member 9 and through groove 24 and into opening 25 in eccentric 23, said pin 59 being forced inwardly past the bottom of said groove 24 by a flat spring 60, held to frame member 9, to force the head of pin 30 out of 80 the enlarged portion 27 of opening 25 into groove 20 in releasing disk 18. It will be observed that, as the lever 16 approaches the end of its throw, the inclined cam portion 22 of groove 20 in disk 18 will engage 85 the projecting head of pin 30 and force said pin into opening 25, thus forcing the end of locking pin 59 out of said opening into groove 24 in eccentric 23, whereupon the pressure of end 56 of spring 54 against the 90 pin 58 carried by eccentric 23 will rapidly rotate said eccentric from the position shown in Figs. 1, 4, 6 and 7, to the position shown in Figs. 3 and 8, thus closing the circuit with a rapid or snap action as the lever reaches 95 the end of its throw. When the eccentric assumes the position shown in Fig. 8, the pin 59 will be forced into the opening 26, forcing pin 29 outwardly until the head of said pin projects into groove 20 in disk 18. 100 The eccentric is then again held against rotation and the parts positioned to release said eccentric when the lever is swung in the opposite direction to break the circuit. The circuit-breaking operation is the reverse of 105 110 that just described and is thought to be obvious.

From the foregoing it will be observed that accidental or careless operation of the switch is practically impossible since the 115 switch lever must be swung through an arc of substantially 180° before the contact-carrying block 35 is moved; that the movable contacts are shifted toward and from circuit-closing position with a rapid snap 120 action; that the movable contacts have a reciprocatory snap movement imparted thereto by a swinging switch handle; and that the entire switch mechanism is inclosed 125 within a protecting casing. 130

It will be seen also that the fuse plugs are inclosed by a box or cover which is shifted into the lower compartment of the switch casing when the circuit is closed, and that the fuse box is so constructed and arranged that the hinged sections thereof cannot be moved to permit access to the plugs when the circuit is closed, the false bottom or partition 6 being so positioned as to embrace the fuse box and prevent the hinged sections 45 and 46 thereof from being swung outwardly except when the switch is in "off" position, in which position the fuse cover is projected above the partition 6. The cover 4 of the outer casing may be provided with a suitable lock, if desired.

What I claim is:

1. In an electric switch, the combination of line terminals, reciprocable circuit-closing means, a motor spring, an eccentric operatively connected to reciprocate the circuit-closing means toward and from circuit-closing position and having two spaced apertures extending transversely therethrough, manually operable means adapted to store power in the motor spring to rotate the eccentric in either direction, a spring-pressed latch reciprocable transversely of the eccentric and adapted to engage in said apertures alternately to hold the eccentric against rotation, a rotary cam controlled by said manually operable means, and a pair of releasing devices reciprocally mounted in the apertures in the eccentric and operable by said cam at the conclusion of successive power storing movements of said manually operable means to disengage the latch from the eccentric.
2. In an electric switch, the combination of line terminals, reciprocable circuit-closing means, a motor spring, an eccentric having a pair of spaced apertures extending transversely therethrough, a strap embracing said eccentric and connected with the circuit-closing means, manually operable means for storing power in said spring to rotate the eccentric alternately in opposite directions, a locking plunger reciprocable transversely of the eccentric adapted to engage in the apertures in the eccentric alternately, a spring normally forcing the plunger toward the eccentric, a pair of releasing pins reciprocably mounted in the apertures in the eccentric and rotatable with the ec-

centric, and means controlled by said manually operable means for forcing said releasing pins alternately toward the locking plunger at the conclusion of successive power storing movements of the manually operable means to disengage the plunger from the eccentric.

3. In an electric switch, the combination of line terminals, reciprocable circuit-closing means, a motor spring, an eccentric operatively connected to reciprocate the circuit-closing means toward and from circuit-closing position, manually operable means adapted to store power in the motor spring to rotate the eccentric in either direction, a locking plunger reciprocable transversely of the eccentric into and out of locking engagement therewith, yieldable means normally forcing the plunger toward the eccentric, a cam rotatable with said manually operable means, and a pair of reciprocable releasing devices carried by the eccentric and operable alternately by said cam to disengage the locking plunger from the eccentric at the conclusion of power storing movements of said manually operable means.

4. In an electric switch, the combination of line terminals, reciprocable circuit-closing means, an eccentric having two spaced apertures extending transversely therethrough, a strap connecting the eccentric with the circuit-closing means, a reciprocable locking plunger at one side of the eccentric adapted to engage in said apertures alternately to hold the eccentric against rotation, yieldable means normally forcing the plunger toward the eccentric, a cam at the opposite side of the eccentric from the plunger, a pair of reciprocable releasing pins mounted in the apertures in the eccentric operable alternately by said cam to disengage the locking plunger from the eccentric, a switch handle rotatable alternately in opposite directions, means connecting said switch handle and said cam to rotate in unison, a coiled motor spring between the eccentric and switch handle having outwardly projecting end portions, and two oppositely extending pins carried by the eccentric and handle and projecting between the end portions of the motor spring.

In testimony whereof I hereunto affix my signature.

LOUIS KELLNER.
